SILENCER

Charles Emory Nelson, Madison, Wis., assignor to
 C. F. Burgess Laboratories, Inc., Chicago, Ill.,
 a corporation of Delaware

Application March 1, 1934, Serial No. 713,438

11 Claims. (Cl. 181—53)

This invention relates to an improved silencer especially applicable to the silencing of the exhausts of internal combustion engines in which occur sound, and also gaseous-pressure waves 5 other than those due to sound.

The silencer of this invention is an improvement over the constructions shown in the Schnell Patent No. 1,811,762, issued June 23, 1931, and Jack Patent No. 1,921,468, issued August 8, 1933, 10 in that it provides a construction whereby the inventions of these patents may be used within a limited space. It often is necessary to limit the length of silencers because of space limitations within the frame members on the under side of 15 automobile bodies. My invention provides means whereby the length required for effective silencing may be obtained even though the available space is limited.

Various specific embodiments of the herein 20 claimed invention are illustrated in the accompanying drawings in which:

Fig. 1 is a side elevation in partial section of one embodiment of my invention;

Fig. 2 is a transverse, sectional view on line 25 2—2 of Fig. 1;

Fig. 3 is a similar view on line 3—3 of Fig. 1;

Fig. 4 is a longitudinal, sectional view of another form of the invention;

Fig. 5 is a transverse, sectional view of the 30 silencer shown in Fig. 4;

Fig. 6 is a longitudinal, sectional view of another form showing concentric inlet and outlet;

Fig. 7 is a transverse, sectional view of another form of the invention;

Fig. 8 is a longitudinal, sectional view of another form of the invention showing the inlet and outlet arranged at the same end of the silencer;

Fig. 9 is a transverse, sectional view of the 40 form shown in Fig. 8;

Fig. 10 is a longitudinal, sectional view of another form of the invention showing a concentric inlet and a concentric outlet;

Fig. 11 is a transverse, sectional view on line 45 11—11 of Fig. 10; and

Fig. 12 is a similar view on line 12—12 of Fig. 10.

Referring to Figs. 1 to 3, the silencer therein 50 illustrated consists of a substantially imperforate cylindrical shell 10 having end flanges 11 and 12. These flanges are provided with an inlet 13 and an outlet 14, respectively. The passage connecting inlet 13 and outlet 14 is made up of four 55 parallel and connected juxtaposed ducts 15, 16, 17 and 18 and the remaining space within the casing is filled with sound and gas-pressure absorbing material 19 which forms the walls of the ducts. Some of these parallel ducts are connected in series. Such absorber may be made 60

of any suitable material such as mineral wool, pumice, aggregate formed from heat expanded clay and known under the trade-mark "Haydite", exfoliated vermiculite and the like bound by a suitable adhesive, preferably an alkali silicate such as silicate of soda. Porous, molded, fired clay shapes also may be used. The preferred composition is a mixture of exfoliated vermiculite and silicate of soda within the ranges of composition described in the above noted Jack patent, the more dense mixtures thereof being preferred. 5

Following is a specific mixture which has given excellent results:

	Pound
Exfoliated vermiculite 6-10 mesh.....	1
42° Bé. sodium silicate (1Na ₂ O: 3.25 SiO ₂ ratio).....	1.2
Limestone dust.....	0.3
Water.....	0.05

This is packed to a density of 30-40 lbs. per cubic foot, 40 lbs. being preferred. When dry this mix has a porosity of 25% to 35%, 28% being a good average. 25

Duct 15, which communicates directly with inlet 13, extends to the opposite end of the cylindrical shell 10. There it connects with both ducts 17 and 18 by means of a transverse passage 20 which is formed by cutting away a portion of the intervening absorbing walls. The two parallel ducts 17 and 18 extend to the opposite end of the shell 10 and are connected with duct 16 by a transverse passage 21 which is also formed by cutting away a portion of the intervening 30 absorbing walls. Duct 16 extends in the opposite direction and connects directly with outlet 14. The gases entering the silencer through inlet 13 travel to the opposite end of the shell 10 in duct 15 to a point adjacent the outlet 14, reverse 35 their direction in transverse passage 20, divide and enter ducts 17 and 18, travel to the end of the shell 10 to a point adjacent the inlet 13, reunite in transverse passage 21 and reverse their direction to travel in duct 16 to outlet 14. 40 45

As the gases pass through the parallel ducts their pressure decreases so that there is a pressure differential between duct 15 and ducts 17 and 18, between duct 15 and duct 16, and between ducts 17 and 18 and duct 16. The greatest difference is between duct 15 and duct 16. The intercommunicating pores and channels of the absorbing material permit some gas to flow or leak from a duct at a higher pressure to one at a lower pressure. I have discovered that the silencer has a greater silencing efficiency when the walls or partitions permit such leakage than a similar construction in which impervious partitions between adjacent ducts are used and which prevent such leakage. The leakage must not be 50 55 60

too great or the silencing efficiency may again drop to a point where the construction does not silence sufficiently. For the best silencing the amount of leakage, which is determined by the 5 physical characteristics of the absorber, that is, the number, size and other characteristics of the intercommunicating pores and channels, has to be determined by experiment for the conditions under consideration.

10 In the silencer illustrated in Figs. 1 to 3, the absorbing material preferably is a molded unit or block. The unit may be molded separately with the necessary ducts and channels and then inserted into the shell 10 and the end flanges 11 and 12 fastened in place. I prefer, however, to mold the unit in the shell 10. The shell 10, without the end flanges 11 and 12 is filled with a plastic mass of aggregate and adhesive such as exfoliated vermiculite and silicate of soda solution. The proportions of these should be such that when the molded product is dried it will have the desired strength and porosity. The proportions may be those set forth in the Jack patent previously referred to. The ducts are 15 then formed by a spearing operation, that is, sharp tipped rods are punched completely through the mixture. These punches may be so formed that they also simultaneously form the transverse passages 20 and 21. The best results 20 are obtained if the spearing of the different ducts is done simultaneously from opposite ends. This simultaneous operation prevents the plastic mixture from accumulating or bunching at one end because of the drag of the plastic mass. The 25 spearing operation as described densifies the material sufficiently and uniformly and forms a smooth-walled duct which is desirable for best results in silencers for the exhaust gases of internal combustion engines.

30 40 After the spearing operation is completed the end flanges 11 and 12 are inserted in the shell. The metallic shell expands more than the molded mixture when subject to temperature changes, and, in order to prevent gas leakage adjacent the 45 end flanges, tubes 22 and 23 are inserted through inlet 13 and outlet 14 for a limited distance into the molded ducts. This construction anchors the molded unit and prevents gas leakage at these points. The molded mass is dried and hardened 50 before it is placed into service.

In the silencer of Figs. 1 to 3 ducts 17 and 18 are in parallel and are formed so that a portion of the shell 10 forms a portion of the walls of these ducts. Among the shapes of ducts which 55 are commercially practical in a circular casing and which have equal cross sectional area the arrangement described above provides the greatest uniform wall thickness and strength. This construction also provides a change in the cross- 60 sectional area in successive ducts, which increases the attenuation of the gaseous-pressure waves passing therethrough.

In another arrangement, Figs. 4 and 5, the transverse ducts connecting the parallel ducts 65 are not molded into the absorbing material. A substantially imperforate casing 24 has end flanges 25 and 26 which contain the inlet 27 and outlet 28, respectively. The molded absorbing material 29 contains three parallel juxtaposed 70 ducts 30, 31 and 32. The absorbing material does not extend to the end flanges 25 and 26 thereby leaving end spaces 33 and 34. Plates 35 and 36 preferably are used to face the end of the absorbing material though these may be omitted. The 75 inlet 27 is connected to duct 30 by a pipe 37. This

pipe preferably projects a short distance into the duct. The outlet 28 is similarly connected to duct 31 by pipe 38.

The gases enter duct 30 through inlet pipe 37 and pass therethrough into end space or transverse duct 34. Here the gases reverse their direction and pass into duct 32 and thence therethrough and into the end space or transverse duct 33. Here they reverse their direction again and pass into duct 31. After traversing the 10 length of duct 31 the gases pass out of the silencer by means of outlet pipe 38. Since the absorber 29 is porous a small proportion of the 15 gases pass through the porous walls from a duct at higher pressure to one at lower pressure. It may be desirable to place the ducts laterally closer together which follow one another immediately in the path of the gas stream and between which there is less differential pressure than 20 there is between ducts which are more remote from one another in the path of the gas stream. This is illustrated in Fig. 5 where duct 32 is closer to either duct 30 or 31 than the latter are to each other. The absorber of this construction preferably is formed by spearing while in the shell 24 25 as described in connection with Figs. 1 to 3 although the molded absorbing member may be molded and dried independently of the shell.

It is obvious that the ducts may be lined with 30 a foraminous material such as a screen or perforated metal as described in the Schnell and Jack patents. Such a lining decreases the erosion of the absorber material and permits the use of 35 absorbing materials which are otherwise destroyed by the destructive exhausts of internal combustion engines.

The constructions of Fig. 1 and Fig. 4 place 40 the inlet and outlet off-center of the end flanges. Fig. 6 shows a construction incorporating the silencer of Fig. 1 with the inlet and outlet concentric of the end flanges. In this construction, I employ a substantially, imperforate casing 39 for the molded absorber 40 containing the juxtaposed parallel ducts. End flanges 41 and 42 are disposed at the ends of the absorber, and the casing 45 is extended beyond these flanges. A second set of end flanges 43 and 44 are arranged at the ends of the casing, thereby forming end volumes 45 and 46. These end flanges contain centrally located inlet 47 and outlet 48, respectively. 50

All of the ducts in the absorbing material may be formed so that the outer shell 49 forms a 55 wall of the juxtaposed parallel ducts 50, 51 and 52 as shown in Fig. 7. In this construction the ducts are lined with perforated metal linings 53, 54 and 55, which are backed with porous absorber 56. This construction also allows gas leakage between the ducts.

In Figs. 8 and 9 a construction is shown in 60 which the inlet and outlet are at the same end of the silencer. Absorbing material 57 is contained in a shell 58. A flange 59 closes one end of the shell. A flange 60 at the other end contains both inlet pipe 61 and outlet pipe 62. These 65 pipes preferably extend a slight distance into juxtaposed parallel ducts 63 and 64. The ducts are connected by curved transverse duct 65. Instead of the curved duct the end space construction of Fig. 4 may be used.

In Figs. 10, 11 and 12 another construction is 70 shown in which the inlet 66 and outlet 67 are concentric with the outer casing 68. An end plate 69 is spaced from the inlet within the casing and forms a space 70 into which the gases pass. The absorbing material 71 is placed in 75

- the casing beyond this end plate 69. The absorbing material is molded to provide ducts 72, 73 and 76 therein. Ducts 72 are adjacent the casing 68. These ducts communicate with the space 5 70 through openings in end plate 69. Ducts 72 are connected with ducts 73 by means of transverse ducts 74 formed adjacent the end flange 75. The gases pass from ducts 72 into ducts 73, the direction being thereby reversed. Ducts 73 extend 10 to the end plate 69 and are connected with central duct 76 by means of a transverse passage 71. Central duct 76 connects with outlet 67, tube 78 preferably extending into duct 76 for a short distance. The gases in ducts 73 pass into central duct 76 and leave the silencer by means of outlet 61 and tube 78.

It is obvious that variations of the described constructions may be made without departing from the principles of my invention. For example, a larger number of juxtaposed parallel ducts may be used, provided that at least two are connected in series. It obviously is not necessary to have the shells or ducts of the shapes shown in the drawings.

I claim:

  1. A silencer for the exhaust gases of an internal combustion engine comprising a plurality of juxtaposed parallel ducts for said gases, at least three of said ducts being arranged in series, sound and gas pressure absorbing material exposed in the walls of said ducts and forming the partitions between adjacent ducts, said absorbing material containing intercommunicating pores and channels, said pores and channels occupying approximately 25 to 35 percent of the volume of said absorbing material, said gases being free to pass through said absorbing material directly from one to any other of said ducts; the passage of said gases through said absorbing material being limited entirely by the porosity characteristics of said material.
  2. The silencer of claim 1 in which the sound and gas-pressure absorbing material comprises a molded mass of exfoliated vermiculite and binder.
  3. A silencer for the exhaust gases of an internal combustion engine comprising a substantially imperforate shell having an inlet and outlet, a plurality of juxtaposed parallel ducts for said gases within said shell, at least three of said ducts being connected in series and connecting said inlet and said outlet, sound and gas pressure absorbing material exposed in the walls of said ducts and forming the partitions between adjacent ducts, said absorbing material containing intercommunicating pores and channels, said pores and channels occupying approximately 25 to 35 percent of the volume of said absorbing material, said gases being free to pass through said absorbing material directly from one to any other of said ducts, the passage of said gases through said absorbing material being limited entirely by the porosity characteristics of said material.
  4. The silencer of claim 3 in which the inlet and outlet are at opposite ends of the imperforate shell and in which there are at least four longitudinal ducts and four transverse ducts at the ends thereof connecting said longitudinal ducts in such manner that the gases reverse their direction of flow twice, in passing from the inlet to the outlet and, at their first reversal, are divided into two streams, and, at their second reversal, are reunited into a single stream.

CHARLES EMORY NELSON
